UNITED STATES PATENT OFFICE.

ROBERT J. CANNON AND JAMES M. WARD, OF DES MOINES, IOWA.

SEAL-LOCK.

SPECIFICATION forming part of Letters Patent No. 276,666, dated May 1, 1883.

Application filed September 25, 1882. (Model.)

To all whom it may concern:

Be it known that we, ROBERT J. CANNON and JAMES M. WARD, of Des Moines, in the county of Polk and State of Iowa, have invented an Improved Car-Door Lock, of which the following is a specification.

The object of our invention is to facilitate the application and improve the operation of locks on sliding doors.

10 It consists in forming and combining a revolving plate or bolt, a hasp, and staples with a sliding door in cars or buildings, as herein-after fully set forth, in such a manner that cleats, shoulders, and obstructions to a sliding motion on the inside or back of the door can be dispensed with and the bolt projected through the door and fixed against the door-jamb to lock and seal the door.

Figure 1 of our accompanying drawings is 20 a face view of a section of a car-door and door-jamb, showing our lock applied and in a locked and sealed position. Fig. 2 is a longitudinal section of Fig. 1. Fig. 3 is a sectional view of the door, showing the bolt and hasp in an 25 unlocked position. Fig. 4 is a transverse section of the door and jamb, and shows the bolt projected inward to engage the jamb. Jointly considered, these figures clearly illustrate the construction, application, and operation of our 30 complete invention.

A represents a sliding car-door, and B one of the jambs or sides of the doorway overlapped by the door.

C is a metal plate and the base-piece of our 35 lock. It is flat and perforated, and adapted to be fixed against the outside flat surface of a door by means of rivets or screw-bolts. It may be wrought or cast metal and vary in size as desired.

40 d is a slot in the longitudinal center and lower portion of the base-piece C.

d' is a corresponding slot through the door A.

f is a metal bolt, in the form of an eccentric, pivoted in the slot d' in the door by means of a 45 screw-bolt, g, or in any suitable way, so that it can be partially revolved in the slots d and d', as required, to throw it in and out of contact with the door-jamb B.

h is a perforated projection on the outside 50 and upper corner of the pivoted bolt d.

m is a hasp adjustably connected with the projection h of the bolt.

n is a staple formed integral with or fixed to the top portion of the base-piece C, in such a manner that the hasp m can be passed over 55 it and secured thereto by means of a key, padlock, or in any suitable way.

r is a second staple or projection, having an eye formed integral with or fixed to the base-piece and door in such a manner that it will extend through the hasp and admit the insertion of a seal, as clearly shown in Figs. 1 and 2.

In the practical use of our lock thus formed and applied, when the door is closed, we simply revolve the pivoted bolt upward and inward by lifting the hasp and placing it over the fixed staples, and there secure the hasp and bolt in fixed positions by means of a key, as shown in Fig. 1, or in any suitable way, so as to retain that portion of the bolt that projects 70 inward against the side of the door way or jamb, as shown in Fig. 4. To unlock we simply free the hasp from the staples and turn it down, to thereby withdraw the bolt from the jamb and into the slot in the door, as clearly 75 shown in Fig. 3, and as required, to allow the door to be moved laterally in its bearings s s relative to the doorway.

By forming a notch, f', in the under side and edge of the pivoted bolt f, as shown in 80 Fig. 2, it is adapted to serve as a latch to engage a bar or pin, f'', that projects from the door post or jamb, and to thereby aid in fastening the door more securely.

We are aware that a perforated drop-piece 85 has been pivoted in the slot of a case and the case fixed over a coinciding slot in the side of a car and a perforated lug fixed to the sliding door in such a manner that the perforated drop-piece could be projected through the coinciding slots of the case and siding to prevent the door from sliding, and locked by means of the coinciding perforations in the drop-piece and the fixed lug; but our device for locking and sealing sliding doors is constructed in such a manner that all its parts can be fixed to and carried by the door, so that there will be no need of fixing a separate lug, cleat, or projection, and obstruction of any kind upon the door or siding to form part 95 of the lock.

We claim as our invention—

1. The plate C, having a slot, d, and staple n, the bolt f, h, having a hasp hinged thereto,

and a sliding door having a slot coinciding with the slot in the said plate C, arranged and combined substantially as shown and described, for the purposes set forth.

5 2. A sliding door having a slot, d' , the plate C d , having staples n and r , the bolt f h , having a hasp hinged thereto, and a sealing device adapted to fasten to the staple r , arranged and combined substantially as shown and described, for the purposes specified.

10 3. The plate C d , having a staple, n , fixed

to a sliding door having a slot, d' , the bolt f h , having a hasp hinged thereto and a notch, f' , in its edge, and the bar f'' , fixed to the doorway frame or jamb of a car or building, arranged and combined substantially as shown and described, for the purposes specified. 15
